[57] CLAIM

The ornamental design for an instrument panel, as shown and described.

DESCRIPTION

FIG. 1 is a front elevation view of an instrument panel showing my new design, it being understood that the broken lines are for illustrative purposes only;

FIG. 2 is an enlarged side elevation view thereof partially in section taken along the line 2—2 of FIG. 1;

FIG. 3 is an elevation view taken along the line 3—3 of FIG. 2;

FIG. 4 is a top plan view taken along the line 4—4 of FIG. 3; and

FIG. 5 is a side elevation view taken along the line 5—5 of FIG. 3.
